UNITED STATES PATENT OFFICE.

JOHN T. FOSTER, OF ARLINGTON, NEW JERSEY.

TEMPORARY BINDER.

SPECIFICATION forming part of Letters Patent No. 224,164, dated February 3, 1880.

Application filed December 16, 1879.

To all whom it may concern:

Be it known that I, JOHN T. FOSTER, of Arlington, county of Hudson, State of New Jersey, have invented certain new and useful Improvements in Temporary Bill or Letter Files, of which the following is a specification.

My present invention relates to that class of files in which the filing-needles are formed in two parts meeting together, the lower part being fixed to receive the papers, while the upper part is movable, so that the upper papers may be transferred to the same and swung away from the others when it is desired to reach or remove one of the under sheets from the fixed needles.

The invention is also an improvement on that class of files shown in a former patent issued to myself April 2, 1878, No. 202,013, in which needles of tubular form with beveled points are used; and it aims to provide files of this kind with a simple and efficient means of transferring the papers from the fixed needles, as well as a means for moving the papers down upon the fixed needles when first placed on file, or when removing the transferred papers from the transfer-needles back upon the fixed needles.

To this end the main features of my invention consist in swinging or partly rotating transfer-needles having a special construction and arrangement relatively to the fixed needles, and in a perforating and stripping device movable upon the needles, as hereinafter fully set forth.

Figure 1 of the drawings annexed presents a plan view of my improved file, and Fig. 2 a side elevation thereof. Fig. 3 is also a side elevation with papers shown on file and a portion transferred to the transfer-needles, which are swung back from the fixed needles.

In the drawings, *a* indicates the base-board of the file, and *b* a light casting riveted on the head end of the board and carrying the operative portions of the file. This casting is formed with an eye at *c*, by which the file may be hung up, and it has also two ears, *ff*, which overlie the base-board, and in the ends of which the fixed filing-needles *d d* are riveted, the said needles rising perpendicularly therefrom to a suitable height. These needles are

preferably of the kind shown in the patent before referred to—that is, tubular—preferably consisting of small brass tubes having their upper ends beveled acutely from one side, so as to form a sharp, yet enduring, chisel-point for readily puncturing the papers as they are placed on file, while the bore of the tubes permits of wires or cords being inserted therein, onto which the papers may be strung and afterward bound into bundles for future reference.

When this kind of needle is used holes are bored through the base beneath them to permit the binding string or wire being passed through. This tubular form of needle is, however, in no way essential to my present improvement, as the needles may just as well be formed of solid wire with conical or with beveled points, if desired.

The casting *b* is also formed with two uprights, *n*, which rise parallel with the fixed needles *d*, and at a short distance therefrom, which serve as a gage for the top edge of the papers, and form, also, a bearing for a cranked trunnion, *e*, similar to that in my aforesaid patent. The ends of this trunnion are equipped with swinging transfer-needles *g*, which curve over and meet point to point with the fixed needles, as shown best in Fig. 2. A spring, *h*, connected at opposite ends with the crank of the trunnion, and with an eye, *k*, on the casting *b*, tends to hold the needles firmly together; but by depressing the finger-plate *l*, projecting from the cranked part of the trunnion, the transfer-needles may be raised and swung away from the fixed needles, as shown in Fig. 3, and when the crank passes over the center the spring will retain the needles in the raised position, as shown in Fig. 3. Radial stops *m*, projecting downward near the ends of the trunnion, strike the flanged portions of the uprights *n*, and limit the overswing of the trunnion and transfer-needles, and retain the same in the position shown in Fig. 3 till allowed to descend by operating the finger-plate, as will be understood.

It will now be observed that when the transfer-needles are raised and swung back, as shown in Fig. 3, the points of the fixed needles become exposed, and the desired papers may be forced over the needles and thus

placed on file, when, by swinging back the transfer-needles, as seen in Fig. 2, the papers will be thus securely retained on file. When, however, it is desired to reach or remove one of the undersheets the upper sheets 5 may be slipped up and back on the transfer-needles, and the same swung away from the fixed needles, as shown in Fig. 3, thus permitting the removal of the desired paper from the file.

It will be observed that the transfer and the fixed needles are of similar thickness, and that their meeting points or ends are beveled similarly, but oppositely, so that the bevels coincide and the needles come in coincident line 15 with each other when the points meet. This forms one of the novel features of my present device, and it has the advantage that it thus avoids any lateral shoulder, protuberance, or 20 obstruction at the junction of the needles, and hence the movement of the papers back or forth thereon is much facilitated.

It has also the further merit that the meeting points of the needles have no tendency 25 to injure each other, as is the case where a conical point on the transfer-needles is arranged to enter the bore of the fixed needles, in which case the tendency is to burr the latter or to split the tube.

30 Another feature of the present invention consists in arranging the axes or trunnions of the swinging or transfer needles on a level, or thereabout, with the top of the fixed needles, as fully shown in Figs. 2 and 3, by which it 35 will be observed that the points of the transfer-needles approach and retire from the points of the fixed needle in line with the level of their points, thus causing the contact of the needles to take place in the least injurious 40 manner.

I also prefer to curve the transfer-needles to a radius from the center of the trunnion, as illustrated; but this is not essential.

The transfer-needles may be prolonged radially and riveted directly into the ends of the trunnion, as seen in Fig. 2, or, in lieu of this, short radial arms may be cast on the trunnions, into which the needles may be riveted at the curved end, as illustrated in Fig. 3, 50 this construction being preferred.

The remaining feature of my invention consists in the stripping device *t*, for moving the papers upon the needles. This preferably consists of a stout wire having its terminal ends 55 bent around the trunnion, as shown best in Fig. 1, so as to be free to turn thereon, while intermediate loops are formed to loosely encircle the needles, and a central loop serves as an operating-handle. The stripper *t* is free 60 to turn upon the needles, and when a paper is to be placed on file it will be observed that by depressing the stripper *t* upon the same it will serve as a perforator to force the sheet down over the needle-points, which it will accomplish more neatly and effectually than can 65 be done by hand.

It will be also observed that when it is desired to remove the papers from the transfer-needles back upon the fixed needles, by closing the needles together and moving the stripper along the same, forcing the papers before it, the papers will thus become neatly and quickly replaced upon the fixed needles, thus rendering the action of the file more convenient and complete.

What I claim as my invention is—

1. The combination, in a file, of a base provided with fixed tubular filing-needles having points beveled from one side, together with swinging transfer-needles formed of solid wire 80 of similar thickness to the tubular needles, and having points of similar bevel, arranged to coincide with the bevels of the tubular needles, and thus avoid injuring the bore or edges thereof, substantially as herein shown 85 and described.

2. The combination, in a file, of fixed filing-needles with swinging transfer-needles pivoted at a lateral distance from the top of the fixed needles and at or about a level with the tops 90 or points thereof, substantially as and for the purpose herein set forth.

3. The combination, in a file, of fixed filing-needles and movable transfer-needles with a pivoted or swinging stripping and perforating device, *t*, movable back and forth upon the latter, substantially as and for the purpose set forth.

4. The combination, in a file, with fixed filing-needles and rotating or curved swinging transfer-needles, of a stripping device mounted on the axes of the said needles and movable over the same, substantially as herein shown and described.

5. The combination, in a file, of fixed filing-needles and swinging transfer-needles with the stripping device *t*, formed of a wire having its terminals bent around the axis of the transfer-needles, and formed with intermediate loops bent to loosely encircle the needles, and freely movable thereon, substantially as herein shown and described.

6. The combination, in a file, of a base provided with fixed filing-needles and swinging transfer-needles, together with fixed uprights 115 *n*, arranged a short distance from the fixed needles, and serving both as a gage or abutment for the papers and as bearings or supports for the axes or trunnions of the swinging needles, substantially as herein shown and described.

7. The combination of a base fitted with fixed filing-needles with swinging transfer-needles having their axes provided with stops 125 *m*, together with the uprights *n*, serving to support said axes and limit the movement of said stops.

JOHN T. FOSTER.
